(57) CLAIM

The ornamental design for a pet kennel cupboard, as shown and described.

DESCRIPTION

FIG. 1 is a perspective view of the pet kennel cupboard;

FIG. 2 is a top view of the pet kennel cupboard;

FIG. 3 is a front view of the pet kennel cupboard;

FIG. 4 is a view of the right side of the pet kennel cupboard. The view from the left side being a mirror image thereof;

FIG. 5 is a rear view of the pet kennel cupboard; and,

FIG. 6 is a bottom view of the pet kennel cupboard.

The broken line showing of environment of FIG. 6 is for illustrative purposes only and forms no part of the claimed design.
